CLAIM

The ornamental design for a hand-held controller for a three-dimensionally articulated medical-industrial invasive probe system, as shown and described.

DESCRIPTION

FIG. 1 is a perspective view of a hand-held controller for a three-dimensionally articulated medical-industrial invasive probe system, showing my new design;

FIG. 2 is a side elevational view thereof, the opposite side elevational view being identical thereto;

FIG. 3 is a top plan view thereof;

FIG. 4 is a bottom plan view thereof;

FIG. 5 is a front elevational view thereof; and,

FIG. 6 is a rear elevational view thereof.

The broken line showing in FIGS. 1-4 is for illustrative purposes only and forms no part of the claimed design.
